COMBINED DISPLAY AND MERCHANTISING RACK FOR TOILETRY PACKAGES OR THE LIKE

George E. Engdahl, Hingham, Mass., assignor to The Gillette Company, Boston, Mass., a corporation of Delaware

Filed May 9, 1962, Ser. No. 70,062

Term of patent 14 years

(Cl. D80—9)

FIG. 1

FIG. 4

FIG. 1 is a front elevational view of a combined display and merchandising rack for toiletry packages or the like showing my new design;

FIG. 2 is an elevational view taken from one side thereof, the opposite side being a mirror image of the side shown;

FIG. 3 is a top plan view thereof; and

FIG. 4 is a rear elevational view thereof.

I claim:

The ornamental design for a combined display and merchandising rack for toiletry packages, substantially as shown and described.
